OF SEATTLE, WASHINGTON, A CORPORATION OF WASHINGTON

COIN CONTROLLED MECHANISM

Application filed January 3, 1930. Serial No. 418,334.

This invention relates to improvements in coin controlled mechanism.

It is a feature of the invention to provide a coin chute having an entrance throat which is proportioned to admit a coin or other token of not more than a prescribed diameter and which does not exceed a given thickness, the throat being shaped in a manner to prevent entrance of a coin or token that is buckled or bent.

10 A further feature of the invention consists in means for arresting coins or tokens in their passage through the chute in such a manner that a plurality of such entities can be inserted, one in superimposed relation to the other or others, and whereby the entities will be separately and successively acted upon to cause a series of vending operations for each genuine coin, the spurious entities being acted 15 upon to prevent a vending operation as a result of the presence thereof, and irrespective of the fact that a token or genuine coin may be of a less than the prescribed diameter.

An object of the invention is to provide 20 means for detecting the spurious from the genuine of the entities by gauging the thickness thereof, the slugs to a great extent, being provided with centrally disposed openings in each, thereby causing a registration of no thickness, while a dime or prescribed coin 25 that is worn too thin, will also be incapable of causing a vending operation.

It is a feature of the invention to provide 30 means acted upon by, and subsequent to the detection operation, for causing genuine coins of the usual thickness to be deflected into or toward a coin box, and coins that are too thin and also spurious entities, to be deflected in a manner to be returned to the purchaser.

40 One of the novel features of the invention resides in detection means operatively connected with mechanism for arresting vending operation, in interdependent relation.

A further feature resides in means for dis- 45 charging steel or other spurious entities before the latter reach the detecting means.

The invention has many other features and 50 objects which will be more fully described in connection with the accompanying drawings and which will be more particularly

pointed out in and by the appended claims.

In the drawings:

Fig. 1 is a view in front elevation of a coin controlled mechanism showing the same in a normal or starting position.

55 Fig. 2 is a fragmentary front view showing the master cam locked as it would appear as a result of insertion of a spurious entity in the coin chute.

Fig. 3 is a similar view showing the parts 60 in a partial vending operation such as would take place after a genuine coin had been inserted in the coin chute.

Fig. 4 is a sectional view on line 4-4 of Fig. 1, with the parts in the same position as 65 in Fig. 1.

Fig. 5 is a sectional view similar to Fig. 4, with the parts in the locked or arrested position shown in Fig. 2.

Fig. 6 is a fragmentary sectional view 70 similar to Figs. 4 and 5 with the parts in the Fig. 3 position.

Fig. 7 is a face view of that portion of the coin chute in which a coin or entity 75 arresting plate is disposed and showing the latter in a position in which an entity is temporarily arrested in its descent in the coin chute.

Fig. 8 is a similar view with the parts in a different position and illustrating a plurality of coins or entities in superimposed 80 relation above the coin arresting device.

Fig. 9 is a horizontal sectional view on line 9-9 of Fig. 1.

Fig. 10 is a view in elevation of the mech- 85 anism shown in Fig. 1, and looking at the rear thereof.

Fig. 11 is a top plan view of the device shown in Fig. 10.

Fig. 12 is a sectional view on line 12-12 90 of Fig. 1.

Fig. 13 is a side view of the coin chute structure partly in elevation but mostly in section.

Fig. 14 is an edge view thereof in elevation looking from the right of Fig. 13.

Fig. 15 is a view in elevation of a centrally 95 perforated slug.

Like characters of reference designate 100

similar parts throughout the different figures of the drawings.

The device of this invention is adapted for use in connection with the vending of any type of merchandise or articles and therefore it has not been shown associated with any special type. I have however, generally indicated at 1, the top of the case or casing in which the mechanism is enclosed and, in this 10 embodiment, the place where a coin, token or like entity will be inserted.

Throughout the claims and the specification, I will use the words "entity" or "entities" generically to coins, slugs and tokens, thereby 15 avoiding alternateness, repetition, and antecedent confusion.

An entrance or throat device is mounted in the top 1, and consists of a plate 2 having a slot 3 of a length to permit insertion of 20 a coin of prescribed or maximum diameter and no larger. The width of the slot 3, is proportioned to limit the insertion of an entity greater than a predetermined thickness, which, in the present instance, is a five 25 cent piece or nickel. Depending from the plate 2, are lips 4 which are so closely spaced that if an entity is bent or buckled, such entity can only be partly inserted, as will be seen by reference to Fig. 12. These lips 30 terminate at 5, in very close endwise relation to the main coin chute, and in practice, these lips are not connected near or at the end portions thereof, the latter being open. It will be understood that these lips 4 will also 35 prevent insertion of an entity of less than the prescribed diameter, if the latter is buckled or bent, and such entity may also be of a reduced diameter with respect to the prescribed diameter for which the device is designed 40 and proportioned to work.

Reference will next be made to the coin chute and the various features of structure with which the latter is equipped.

The entrance to the coin chute is indicated 45 at 6, closely disposed to the terminals 5, of the lips 4, as shown in Figs. 1 and 12, so that the lips 4 will guide the inserted entity into the coin chute before such entity has passed through or from between the lips 50 4, as will now be clear. This coin chute has what will be termed an entrance section 7, which is vertically disposed for gravity descent of an entity therethrough or therein. Said coin chute has an initial or slug discharge section 8 which is shown disposed in 55 offset relation to the entrance section 7, slanting downwardly and laterally as shown in Fig. 1. Depending from said discharge section 8, is what I will term a chute operating section 9, having a final discharge end 10.

Extending laterally and diagonally downwardly from the discharge section 8, is a slug section 11, having a discharge outlet 12. As will be seen more particularly in Figs. 13 65 and 14, the slug section 11, junctures with

the section 8 in a manner to form a release passage 13 for what I will term "magnetic" entities, such for instance as steel slugs. A magnet 14, preferably although not necessarily of a permanent type, is secured to a 70 mounting 15, suitably anchored to the coin chute. The poles 16, of said magnet extend across the bottom of section 8, and as a steel or like slug rolls down the chute, it is attracted by the magnet and thereby diverted 75 into the slug section 11, as will now be clear. Means such as a thin non-ferrous strip 17, may be disposed as shown to prevent an attracted entity from "freezing" to the poles of the magnet 14, thereby insuring its discharge downwardly in chute 11. Said strip 17, may be anchored at 18.

Thus it will be seen that I have provided means acting intangibly or magnetically for discharging that type of entity subject to 80 magnetic action before it can reach the operative section of the coin chute.

Reference will next be made to the operating section of the coin chute.

A frame or base 19 is provided on which 90 the mechanism of the invention is mounted and the operating section 9, and the slug section 11, are suitably secured to this base 19. This base 19 is adapted to be secured in the structure in which the vending and coin controlled mechanism are disposed. At the discharge end 10, of the coin chute, the base is cut-away or bifurcated to form substantially 95 forked sections 20 and 21, to be later described.

In further description of the operative section 9, of the coin chute, reference will next be made to a feature whereby all entities, whether genuine coins of prescribed diameter or less and all slugs except those magnetically deflected, will be arrested, or temporarily arrested in the coin chute section 9, for purposes of detection of their character. 105

In the description of this feature, reference will be made to Figs. 4, 5, 7 and 8. An 110 entity arresting means is provided which, in the present construction takes the form of a member or plate 22. This is a rocking plate and preferably a floatingly mounted plate, and means which will later be described, is provided for imparting rocking movement to said plate.

Said plate 22, has a set of studs 23 spaced for arresting entities of normal or prescribed 115 diameter, such for instance as a five cent piece, as shown in Fig. 7. These studs 23, which, in the present construction are the lower set, are spaced apart sufficient to permit a dime or any entity of less than a 120 prescribed diameter, or substantially so, to freely pass between said studs. The outer wall 9' of the coin chute, is provided with openings 24, through which said studs 23 125 may be projected through the outer wall 9'. 130

and across the chute passage, as shown in Fig. 4.

Said plate 22, is also provided with a set of arresting studs 25, which in this construction, is the upper set of studs and which are sufficiently closely spaced not only to arrest an entity of prescribed diameter but one of less than such diameter, such for instance as a dime. The outer chute wall 9' is provided with openings 26 for projection of studs 25 into the coin chute as shown in Fig. 5. By reason of the fact that the plate 22 is floatingly mounted, I preferably taper the studs 23 and 25, and the openings 24 and 26 are somewhat enlarged to afford ample clearance. It will be seen from Fig. 8, that the upper studs 25, are capable of supporting a plurality of superimposed entities irrespective of whether they are of the prescribed diameter, the importance of which will be later described.

Reference will next be made to the means for floatingly mounting the plate 22.

At its upper corners, the plate 22 is cut away as shown at 27 and guiding pins 28, mounted on wall 9' of the coin chute, extend outwardly through such cut away portions 27, and serve as a guiding means for rocking movement of the upper portion of plate 22.

The lower corners are shown cut away or interrupted at 29 and a bail 30 extends across the lower margin of said plate and the ends of said bail, as indicated at 31, in Fig. 8, extend inwardly and form guiding studs or pins for coaction with the cutaway portions 29.

The guiding pins 31 are anchored to the wall 9' of the coin chute. As the lower portion of plate 22 is not the actuated portion, it is advantageous to employ a bail so that the bight of the latter will prevent the lower portion of the plate 22 from moving outwardly too far.

Means such for instance as springs 32, anchored at 33, to the coin chute and having their free ends 34 bearing against the plate 22, normally serve to urge the plate toward the coin chute, and the thrust exercised by said springs is near the horizontal center of the plate 22.

Reference will next be made to the means employed for imparting rocking movement to plate 22.

What I will term a master cam, to be later described in full, is indicated at 35, and is rigidly mounted on a cam shaft 36, which latter is a main operating shaft. This shaft 36, is journalled in bearings 37 and 38 that are mounted on or cast integral with the base 19, and project from opposite sides thereof.

Said cam, which in the present construction, is rotary, carries an actuating and releasing cam stud 39. An actuating lever 40, is pivoted at 41, to the base 19, in the rear of cam 35, and is provided with an actuating

duced with respect to the radius of stud 39, and adapted, when engaged by stud 39, to impart a downwardly thrust to plate 22.

Said lever 40 is urged by a spring 43, anchored at 44 and connected with said lever at 45, toward said stud 39, and thereby functions to impart an upward thrust to plate 22. Lever 40 has an elbow 46, provided with an actuating terminal 47, which latter slidably engages the slot 48, of an actuating or rocking arm 49, that is rigidly secured to the upper portion of plate 22, as will be clearly seen by reference to Figs. 1 and 4.

Reference will next be made to a novel means for detecting the character of entity that is arrested by plate 22.

A lever 50, which I will term a detecting lever, is hinged to the base 19 at 51, to swing in a substantially horizontal plane about a substantially vertical axis. A spring 52, normally urges said lever 50, toward the coin chute. Extending transversely through said lever 50, is a coin detecting stud 53, more clearly shown in Fig. 9. Thus stud 53, may be advantageously in threaded engagement with said lever 50, and a lock nut 54, provides means for securing the stud 53 in adjusted positions. The plate 22, is provided with an opening 55, through which said stud 53 freely extends, and an opening 56, in the wall 9' of the coin chute, permits the stud 53 to extend into the latter, and into engagement with an entity that has been arrested by studs 23, of plate 22, for purposes of detection.

The free end 57, of said lever 50, is provided with a slotted or lost motion connection with one arm 58, of a bell crank lever, the remaining arm 59 of which, is pivoted at 60, to a boss 61, projecting from base 19. Arm 58, is shown provided with a slot 62, and a pin 63, mounted on lever 50, completes the slotted connection before referred to.

Reference will next be made to instrumentalities operatively interposed between the master cam 35 and lever 50, whereby an interdependent relation is established between said cam and said lever.

What I will term a break-joint pawl, is shown in two parts and the pivoted or supporting part consists of a pawl arm 64 which is pivoted at 65, to boss 61. A pawl part or portion is designated at 66 and is shown to be of U-shape, in cross section. Said pawl portion 66, is united with the supporting portion 64, by a pivot 67, and the lower end 68 overhangs the pivotal connection so that a break joint movement of the parts toward a straight or linear position, is limited to the relationship shown in Fig. 1. The cam end 69 of pawl section 66 partly laps the side faces of the cam 35 and rides on the periphery thereof, as clearly shown. I preferably make the part 64 in the form of a bell crank, an arm 70, thereof, forming a suitable lever-

age for connection of one end of a spring 71, the free end of which extends slidably through a lug 72, on pawl 66. This spring is arranged and tensioned to urge the parts 5 66 and 64 toward and into the position shown in Fig. 1, but permits the parts to buckle or break joint as shown in Fig. 2, for a purpose to be more fully described later on. In actual 10 practice, a spring is not absolutely necessary 15 in order to maintain the pawl parts 66 and 64 in engagement with the cam 35 although a spring tension makes the pawl action more responsive. Therefore, I have shown a tension spring 73, having its lower end connected to arm 70 to urge the pawl end 69 into engagement with cam 35.

The pawl member 64, is provided with an opening 74, into which projects a lug 75, forming a part of arm 59, thereby forming 20 an operative connection between the break-joint pawl and the detecting arm 50. Thus it will be clear from Fig. 9, that as the break-joint pawl is shifted to the right of its pivot 65, the bell crank arm 58 will be shifted outwardly from base 19, thereby moving arm 50 in the same direction and withdrawing stud 53 slightly from the coin chute, and that a movement of the break-joint pawl to the left of Fig. 1, or as viewed therein, the lever 50 25 would be allowed to move toward the base 19 and cause a corresponding entrance of stud 53 into the coin chute. The operation of this portion of the invention will be more fully described later on.

35 In order to make the construction clear, I have just described the separate parts 64 and 66 of the break-joint pawl but hereafter, I will refer to this feature as the "break-joint pawl" and will provide it with a generic 40 designation A.

Before entering into a description of the master cam 35, I will first describe a check pawl, the function of which is to check the cam 35 against retraction from an operative- 45 ly advancing position or movement.

Said check pawl is indicated as a whole at 76 and is pivoted at 77 on a boss 78, which projects from base 19. Said pawl has a pawl arm 79 which is provided with a ratchet pawl 50 foot 80 which is flat or straight and which is adapted either to engage an arresting notch in the cam 35, to be later described, or engage ratchet tooth portions of said cam. Said pawl has an arm 81, that is adapted to 55 be spring actuated, and for convenience, I employ spring 73, to which said arm 81 is connected. This spring 73 maintains said foot 80, in engagement with cam 35.

Said check pawl 76 performs additional 60 functions which will next be described in detail.

An arm 82 of said pawl is connected with 65 an operating rod 83 which extends downwardly between the cam 35 and base 19 and is connected at its lower end 84, to an arm

85, as more clearly shown in Figs. 4 and 5. This arm 85 is mounted on a coin diverter shaft 86, journalled in bearings 87 and 88, formed on forked sections 21 and 20, respectively, of base 19. Mounted on said shaft 70 86, is an improved coin or entity diverter which, as shown, consists of a U-shaped sheet of material having a bight 89 and limbs 90, and said limbs 90 may be secured to said shaft by means indicated at 91. Thus it will 75 be seen that the top of this diverter is spaced some distance below the discharge end 10, of the coin chute and the lower edges of the limbs extend slightly below the shaft 86, to 80 which they are mounted.

The function of this diverter is to divert genuine coins rearwardly into a coin box, generally indicated at 92, and to divert slugs or unvendable coins forwardly into a suitable return receptacle, which is generally indicated at 93, and which is accessible to the purchaser while of course the coin box 92 is inaccessible except to the service man for the machine.

85 A counter 94, is mounted on section 21, and is provided with an actuating arm 95, the latter being pivoted at 96, to a link 97, the remaining end of which is jointly connected with arm 85, to the lower end 84, of operating rod 83. Thus, the operating rod 83 functions to actuate the diverter and the counter, in a manner to be more fully described in the subsequent description of the operation.

I will next describe the structure and purpose of the master cam. 100

Although a circular and rotary form of cam is not essential to my invention, this form is herein shown mounted on cam shaft 36. Said cam 35 is provided with what I will term an arresting notch which is indicated at 98, and which is a somewhat elongated and rectangular type of notch having a terminal or arresting end 99, adapted to coact with the break-joint arresting pawl, and a terminal or arresting end 100, which is adapted to coact with the foot 80, of the check pawl 79. This arresting notch is disposed radially inwardly from the balance of the cam's periphery, as will be clearly seen, and the purpose of which will be later developed. The major peripheral portion of the cam 35, as indicated at 101, has the greatest diameter and is provided with ratchet teeth adapted to coact with pawl 79, to prevent any retractive movement of cam 35 115 from the rotative movement necessary to complete a vending operation. The vending movement of cam 35, is in a clockwise direction, viewing Fig. 1.

The terminal 102, of the ratchet portion 120 101, constitutes an operating hill of the cam from which descends a declining vale 103, also of operating significance, and which terminates at the arresting end 100, of notch 98. From the opposite end 99, of said notch ex- 130

tends a concentric hill 104 which merges into an inclining vale 105, the latter terminating at the remaining operating hill 106, which is the opposite terminal of the ratchet portion 5 of the cam 35.

Reference will next be made to an improved brake mechanism which retards advance of the cam during a vending operation of the latter and which is designed and constructed 10 greatly to relieve the break-joint pawl of strain in arresting the master cam from a vending operation.

Referring to Figs. 10 and 11, a hub 107 is rigidly mounted or keyed to shaft 36 and is 15 provided with a braking arm 108 which may be formed integral with said hub 107 and a gear wheel 109, which latter is in one piece with said hub. A braking lever 110, is pivoted at 111, to said base 19 and is provided 20 with a minor braking surface 112 and a major braking surface 113, with which said braking arm coacts. A spring 114 has one end anchored at 115, to base 19, and the remaining end connected at 116, to the free end 25 of said lever 110. When the parts are in the normal starting position shown in Fig. 1, the braking arm 108 is in the position shown in Fig. 10, which is an abutting relation to the arm 110, thereby affording one of the 30 greatest moments of resistance to vending advance of shaft 36, even though the spring 114 is not under much tension. However, the resistance increases as the end of arm 108 rides on arm 110, as shown in dotted lines, 35 and the operation of which will be more fully described later on. In addition to acting as a yielding brake, this device causes the vending mechanism automatically to return to a starting or normal position after a spurious 40 entity has been rejected.

Before entering into a detailed description of the operation, it may now be informative to state specifically certain functions that the device is adapted to perform so that the latter will be clarified in the light of the preceding description.

The throat device, shown in Fig. 12, will prevent entrance of entities that are mutilated by being buckled or bent, and it will 50 prevent entrance of entities that are either too thick or of a too great diameter.

The magnet will cause discharge of what I term "magnetic entities" such for instance as slugs made of iron or steel, before such 55 entities reach the detector.

The arresting plate and detector will permit coins or slugs of a small diameter to immediately pass through and be returned to the purchaser, without effecting any vending 60 or other operation of the mechanism. Genuine coins of prescribed diameter that are worn too thin, will also be rejected, likewise slugs of the same character, and slugs that have a central perforation will also be rejected.

The operation will now be described in detail.

Although not essential to the invention, the machine shown is designed for operation with nickels. However, it is capable of being proportioned for dimes, quarters or in fact any denomination of money, or rather currency.

If a dime should be inserted in the present machine, it could readily pass through the throat device 3, down the chute sections 7, 75 8 and 9, and by reason of the fact that in a starting or normal position the rocking plate 22, is always in the Fig. 4, position, the dime would not be arrested by the withdrawn studs 25, and the projected studs 23, are spaced far 80 enough apart to permit a dime to pass through or between them. Thus the dime would discharge at 10, and as the diverter 90, is always in the Fig. 4, position when the mechanism is in a normal or starting position, 85 the dime would be diverted into the return receptacle 93, which is accessible to the purchaser. This would all occur before the purchaser could operate the usual turn knob B, with which devices of this character are 90 equipped.

However, suppose the purchaser, after depositing a dime, turned the knob B, in a clockwise direction with a view of causing a vending operation, which is the only way it 95 can be turned by reason of the check pawl 79, engaging the arresting notch 98, then, and in that event, a movement would result which I will next describe.

The cam 35 would be turned from the Fig. 1 to the Fig. 2, position, and as nothing would be interposed between the detection stud 53 and the back wall of the coin chute, this stud 53 would be free to enter the chute to the fullest extent under the action of spring 52. 100 Such movement would (Fig. 9) cause arm 50 to move toward base 19 and lug 75 would move the break-joint pawl A, to firmly engage the periphery of cam 35 and thereby cause the end 69 to enter notch 98, and as abutment 99 105 engaged end 69, a further movement of the cam 35 would "break" the "break-joint" pawl into the Fig. 2, position thereby locking the sections 64 and 66, and preventing further rotative movement of cam 35. The upper end 110 of section 64, has a flattened portion 64' that engages the bight 66', of section 66, as clearly shown in Fig. 2. As this movement is being effected and arrested, arm 108 (Fig. 10) rides onto the abutment portion 113, tensioning the spring 114 and thus resists such movement thereby taking much of what would otherwise be a strain subjection from the break-joint pawl. As the knob is released, recoil of spring 114 quickly restores the parts from the Fig. 2, to the Fig. 1, position, with the arms 108 and 110 in the full line position in Fig. 10.

In this arrested movement of the mechanism, the cam stud 39 would have moved out 130

of engagement with cam 42, and into the Fig. 2, position, thereby releasing lever 40 for movement by spring 43, into an upward position as far as slotted arm 49 would permit. 5 This would cause the end 47, of lever 40, to slide to the outer end of slot 48, as shown in Fig. 5, thereby rocking plate 22 from the Fig. 1 to the Fig. 5, position, wherein the upper studs 25 would be projected into the chute 10 and the lower studs 23, withdrawn. Should the purchaser deposit a dime and turn knob B before the dime had reached a point in its decent adjacent the plate 22, the above operation would take place even if the studs 25 15 were projected into the coin chute thereby arresting the dime before the latter reached plate 22. In the following restoring movement, above described, the plate 22 would be restored to the Fig. 1, position, thereby releasing the dime for gravity passage between studs 23, and out through the discharge end 10, as will now be clear.

Suppose a ferrous entity were deposited, it would be attracted by the magnet poles 16 25 and shifted from its path down section 8, into discharge section 11 and out through discharge end 12, as shown in Fig. 13, and would never reach the detecting mechanism. The 30 non-ferrous strip 17, would prevent the ferrous entity from "freezing" to the magnet poles 16.

Now it will be assumed that a slug had been inserted having a central perforation as shown in Fig. 15. If this slug was of the 35 same diameter as a nickel, and of non-ferrous metal, it would descend in the coin chute into engagement with studs 23 and would be arrested thereby in a position for detection, and the resulting rejection will now be described.

40 Assuming that such perforated slug descended to the position shown in Fig. 7, and was arrested by studs 23, it will be seen that the perforation would be centered with respect to the detection stud 53 (Fig. 9). Thus, 45 the operation would be much the same as was described in connection with movement of the parts when a dime was inserted. By turning the knob B clockwise, the break-joint pawl would ride down the vale 103 thereby permitting spring 52 to move arm 50 toward base 19 and cause detection stud 53 to enter the coin chute. As the opening in the slug would not arrest movement of stud 53, the break-joint pawl end 69 would ride into 55 notch 98 and engage terminal 99 and further clockwise movement of cam 35 would cause the pawl to break at its joint as shown in Fig. 2, and arrest further movement of the cam. As the knob B was released by the purchaser, the parts would be restored to the Fig. 1, position, whereupon the plate 22 would be rocked to the same position. However, in movement of the parts to the Fig. 2, position, the plate 22 would be rocked to the Fig. 4, 60 position, thereby releasing the slug just as

soon as the stud 53 had been slightly withdrawn, or, in some adjustments, and in fact in most adjustments, the stud 53 would never enter the coin chute far enough to project into the perforation in the slug. Thus, in the latter event, just as soon as the plate 22 was rocked to the Fig. 4, position, the slug would be released and would be shifted by the diverter 90, into the pocket 93. The stud 53 is, as heretofore explained, adjustable in arm 50 in accordance with the extent to which it should be projected into the coin chute. 70 75

I will next describe the operation which takes place when a nickel or entity of genuine character is inserted into the chute and a vending operation takes place.

When a genuine coin of prescribed denomination has been inserted into the coin chute it will descend therein and be arrested by studs 23, in the position shown in Figs. 4 and 7. 80 Rotative movement of knob B in a clockwise direction will permit break-joint pawl, after riding over peak 102, to descend vale 103, and on this movement, arm 50 will project stud 53 into engagement with the arrested nickel 90 thereby arresting further inward movement of arm 50. Of course, the parts are so timed that studs 23 will not be withdrawn from the coin chute until stud 53 has engaged and held the nickel for a momentary period. The interposition of the nickel between stud 53 and the back wall of the coin chute prevents arm 50 from moving toward base 19 far enough to cause bell crank 59 to move the break-joint pawl end 69, into said arresting notch 98. 100 Therefore, instead of said end 69 entering said notch and abutting against terminal 99, thereof, and arresting movement of cam 35, as it does when a perforated slug or a dime or a nickle worn too thin, are inserted, the 105 said end 69 rides over said notch 98 and does not engage it. Thus, detection has been accomplished showing that the entity acted upon is the right thickness, and hence, a vending operation must take place. As end 69 passes over notch 98, it rides on operating hill 104, of cam 35 and this causes a clockwise movement of the break-joint pawl which, viewing Fig. 1, causes arm 50 to move outwardly away from base 19, and thereby released the detected nickel for discharge from the coin chute. As the break-joint pawl has passed the arresting notch, there is nothing to prevent the knob B from being turned a 110 full revolution to complete a vending operation. 115

It will of course be understood that before or when the parts have reached the Fig. 3, position, stud 39 will have released cam 42 and lever 40 will have been elevated by spring 43, thereby tilting plate 22 into the Fig. 5, position, thus to remain until stud 39 again engages cam 42, and lowers lever 40. The upward and downward thrust of the end 47, in slot 48, of arm 49, causes rocking move- 120 125 130

ment of plate 22 and the guide pins 28 and 31, limit any vertical movement thereof, as will now be clear.

As the cam 35 is turned, it will be seen that 5 check pawl 79, has ridden upwardly on vale 105, and onto the concentric ratchet portion 101, as shown in Fig. 3, which movement has been made in time to lower rod 83 and shift the diverter 90 from the Fig. 4, position to 10 the Fig. 5, position, so as to divert the genuine coin into the coin box 92. This downward movement of rod 83, also moves arm 95, of the counter, downwardly, which thus constitutes one portion of actuation thereof. When 15 the cam 35 is advanced far enough so that the check pawl 79, rides inwardly on vale 103, then, rod 83 is lifted or moved upwardly and the counter is finally advanced to indicate that a vending operation has been effected. 20 As it requires first a downward and then an upward movement of arm 95 to register a counting advance, it will be clear that the counter is never thus operated on a partial or arrested movement of cam 35. 25 Reverting to the combined braking and returning means shown in Fig. 10, it will be clear that as the cam 35 is advanced and the check pawl 79 is riding on the ratchet portion, arm 108 will be riding on arm 110, in a 30 contra-clockwise direction, viewing Fig. 10, and after the arm 108 has been elevated out of contact with arm 110, the latter is instantly returned by spring 114 and the abutment 113 is brought into a position to yielding 35 arrest the cam 35, which has now been returned to normal.

Thus it will be seen that the check pawl 79, is positively effective in preventing retractive or contra-clockwise movement of the 40 cam 35, viewing Fig. 1, and that the returning means yieldingly resists clockwise movement of said cam 35 from a normal or starting position and returns it to such position from a relatively slight advance therefrom. 45 As heretofore stated, spring 73 is connected at its opposite ends to yieldingly maintain pawl 79 and break-joint pawl A, in engagement with the cam wheel 35, and as one spring is capable of performing these two functions, it is thus employed. However, spring 50 73 is of such lighter tension than spring 52 as to make the latter dominant and primary.

It is believed that the device of this invention will be fully understood from the foregoing description and while I have herein shown one specific form of the invention, I do not wish to be limited thereto except for such limitations as the claims may import.

I claim:—

60 1. In a coin controlled mechanism, a coin chute adapted to receive a plurality of superimposed genuine and spurious entities, a rocking entity controlling frame having a lower set of studs for arresting an entity in a detection position and an upper set of studs

for arresting the remaining entities from entering a detection position, a detection device movable into a detection position with respect to a correspondingly positioned entity to determine the character of the latter, and 70 means for rocking said frame to alternately dispose said sets of studs in arresting positions in said chute.

2. In a coin controlled mechanism, a coin chute adapted to receive entities, a rocking entity controlling plate having sets of entity arresting studs, one set of studs being spaced apart to arrest an entity of a diameter less than the prescribed diameter and the remaining set being spaced apart to permit passage of such smaller diameter entity and close enough to arrest an entity of prescribed diameter, means for rocking said plate to dispose either set of studs in an arresting position in said chute, and detection 80 means operating against an arrested entity of prescribed diameter.

3. In a coin controlled mechanism, a coin chute for receiving entities, an entity controlling device for temporarily arresting an 90 entity in a detection position in said chute, detection means movable into said chute a predetermined distance into momentary engagement with an entity of prescribed thickness or moving into said chute but not engaging a perforated or too thin entity, and means for actuating said device to release the arrested entity prior to release of a genuine entity by said device to prevent a vending operation except when a coin of normal 100 thickness is deposited in the chute.

4. In a coin controlled mechanism, a coin chute for entities, a floating, rocking plate having upper and lower sets of entity arresting studs adapted alternately to be projected into said chute as said plate is rocked, fulcrum guide pins for guiding said plate in its rocking movement, a spring normally acting to move said plate toward said chute, a slotted arm fixed to said plate and projecting laterally of the plane thereof, a lever slidable in said slotted arm and being actuated to impart thrusts to said plate in different directions in the plane of said plate to rock the latter into different entity arresting positions, and means for detecting an entity while the latter is arrested by said lower set of studs. 110 115

5. In a coin controlled mechanism, a coin chute adapted to receive an entity for thickness detection thereof preliminary to a vending or non-vending operation, means for arresting an entity in a detection position in said chute, a spring actuated detector arm having a detector stud movable into said chute for engagement with an entity of the prescribed thickness, a master cam having an arresting notch, a break-joint pawl actuated by said arm to engage said pawl with said cam and shifting said pawl into said notch to "break" said pawl and cause the latter 120 125 130

to arrest vending movement of said cam when a perforated or too thin entity permits said stud to enter too far into said chute, or holding said pawl free from said notch on engagement of said stud with a normal thickness entity thereby permitting vending movement of said cam.

6. In a coin controlled mechanism, a coin chute adapted to receive entities, means for arresting an entity in said chute in a detection position, a spring actuated detection arm provided with a detection stud adapted to enter said chute, a master cam provided with a pawl arresting notch, a pawl operatively connected with and urged by said arm into engagement with said cam, said cam having a vale permitting movement of said stud into said chute for engagement with a normal thickness entity to prevent said pawl from engaging said notch or permitting further movement of said stud toward a too thin or perforated arresting entity to permit said pawl to engage said notch and prevent a vending operation, and means for automatically restoring the parts to a normal position from a partial or non-vending position.

7. In a coin controlled mechanism, a counter, a coin chute for entities provided with a discharge end, entity arresting and detecting mechanism for said chute, a diverter below said discharge end for diverting spurious entities in one direction and genuine entities in another direction, a check pawl for operating said counter and diverter, and a master cam having a series of ratchet teeth for engagement with said check pawl to prevent retractive movement of said cam, and said cam having hill and vale portions for actuating said check pawl to operate said counter and diverter.

8. In a coin controlled mechanism, a coin chute adapted to receive entities, means for arresting an entity in said chute for detection purposes, means for detecting spurious from genuine entities while the entity is arrested in said chute, a pawl connected with said means to operate the latter or be operated thereby, a master cam engaging said pawl, said cam having a portion permitting operation of said pawl by said means responsive to a spurious entity for arresting a vending operation or operating said pawl responsive to a genuine entity to permit a vending operation, and said cam having portions for causing said pawl to operate said means to retract the latter.

9. In a coin controlled mechanism, a coin chute adapted to receive entities, means for arresting an entity in said chute for detection purposes and then releasing such entity, means for detecting spurious from genuine entities while the entity is arrested in said chute, a device connected with said means to operate the latter or be operated thereby, and an element engaging said device and

having a portion permitting operation of said device by said means responsive to a spurious entity for arresting a vending operation or operating said device responsive to a genuine entity to permit a vending operation.

In witness whereof, I have hereunto set my hand.

WELLS H. CLAUSSEN.
